A. V. Hill,

Cutting Leather,

No 66,589,

Patented July 9, 1867.

Fig. 1.

United States Patent Office.

ALBERT V. HILL, OF LIMESTONE, NEW YORK.

Letters Patent No. 66,589, dated July 9, 1867.

IMPROVED TUG-TRIMMER.

The Schedule referred to in these Letters Patent and making part of the same.

TO ALL WHOM IT MAY CONCERN:

Be it known that I, ALBERT V. HILL, of Limestone, in the county of Cattaraugus, and State of New York, have invented a new and improved Tug-Trimmer; and I do hereby declare that the following is a full, clear, and exact description thereof, which will enable others skilled in the art to make and use the same, reference being had to the accompanying drawings, forming part of this specification, in which—

Figure 1 is a top view of my improved tug-trimmer.

Figure 2 is a detail cross-section of the same taken through the line $z z$, fig. 1.

Similar letters of reference indicate like parts.

My invention has for its object to furnish an improved instrument by means of which the edges of a tug may be conveniently, accurately, and quickly trimmed; and it consists in the angle knives and adjustable blocks, in combination with the adjusting-screw and frame, having a scale marked upon it, and in the combination of the roller, roller-frame, and screws with each other and with the main frame of the instrument, the whole being constructed and arranged as hereinafter more fully described.

A is a U-shaped frame, to the ends of the arms of which is secured a cap, B, having a hole through its centre for the reception of the screw C, which passes through it in such a way that while free to turn it can neither move forward nor back. The forward end of the screw C rests and revolves in a socket in the other end of the frame A. D is a crank attached to the outer end of the screw, by means of which it is operated. E is a block secured to the end of the frame A by a screw or screws, and the inner side of which is notched, as shown in the drawings, to allow the shavings to escape readily. F is a block similar in construction to the block E, except that its lower part is extended down through the opening in the frame A, and has a hole formed through it for the passage of screw C, said hole having a screw-thread cut in it corresponding with the thread of the said screw, so that by turning the screw C the block F may be moved forward or back to adjust it to the required width of the tug. To enable this to be done quickly and accurately a scale is formed upon the frame A, as shown in fig. 1. G are the knives, which are bent at right angles that they may be attached to the ends of the blocks E and F, and project along their sides in proper position for trimming the edges of the tugs as they are drawn through the machine. H is a frame, to the end bars of which, beneath the longitudinal bar, is pivoted the roller I to hold the tug down close to the frame A as it is drawn through the machine. The roller I is held down to its place and enabled to adapt itself to the thickness of the various tugs by the coiled wire springs J coiled around the end bars or screws of the frame H and pressing against the longitudinal bar of said frame, as shown in fig. 2.

What I claim as new, and desire to secure by Letters Patent, is—

1. The knives G and blocks E and F, in combination with the adjusting-screw C and frame A, having a scale marked upon it, substantially as herein shown and described and for the purpose set forth.
2. The combination of the roller I, roller-frame H, and coiled springs J with each other, and with the frame A, substantially as herein shown and described and for the purpose set forth.

ALBERT V. HILL.
